RING STRUCTURE FOR CONNECTING CANS IN SUPERPOSED RELATION

John Henchert, River Forest, Ill., assignor to Continental Can Company, Inc., New York, N. Y., a corporation of New York

Application February 15, 1957, Serial No. 640,454

7 Claims. (Cl. 220—23.83)

The invention relates generally to metallic receptacles and primarily seeks to provide a novel ring structure for connecting cans in superposed relation.

It sometimes happens that in the marketing of products in cans a customer will want to make a combination or bargain deal, selling at a special price a can of smaller capacity or diameter along with a can of larger capacity or diameter, the cans having contents of the same kind or of different kinds. An object of the present invention is to provide a novel ring structure including a skirt, roll crimped or securely curled onto the seam at the top of the larger can, and an upstanding ring rib within which to receive the seam at the bottom of the smaller can, said rib having indents or nibs under which said smaller can seam can be snapped and which serve to removably attach the superposed smaller can to the supporting larger can.

Another object of the invention is to provide a can connecting ring structure of the character stated wherein there is included a can supporting shelf extending inwardly from the upstanding ring rib and whereon the bottom seam of the superposed can may rest, and a downwardly turned annular flange or wall engageable as a supporting column against the top end closure of the supporting larger can.

A further object of the invention is to provide a can and connecting ring combination wherein the superposed cans are of the tear strip type, each having a tear strip winding key attached centrally on its top closure, the key on the larger supporting can being readily accessible through the central opening in the connecting ring after the smaller supported can is removed from its snapped in mounting.

With the above and other objects in view that will hereinafter appear, the nature of the invention will be more clearly understood by reference to the following detailed description, the appended claims and the several views illustrated in the accompanying drawings.

In the drawings:

Figure 1 is a side elevation and in part vertical cross sectional view illustrating the improved connecting ring structure per se, prior to attachment thereof to the cans to be connected thereby.

Figure 2 is a side elevation and in part vertical cross section illustrating two cans in superposed relation and connected by the connecting ring structure.

Figure 3 is a plan view illustrating the connected can and ring combination shown in Figure 2.

Figure 4 is an enlarged fragmentary sectional view illustrating a portion of the connecting ring and can portions connected thereby.

In this example disclosure, the can connecting ring structure is shown as comprising a flat horizontal ring body 5 merging at its periphery into a downwardly turned skirt 6. Inwardly, the body 5 merges into an upwardly and inwardly inclined wall 7 merging through an inwardly and downwardly turned curve or rib 8 into an

2

upright wall 9, inwardly of and concentric to the skirt 6. The upright wall 9 merges at its lower extremity into an inwardly turned horizontal shelf 10, and the shelf merges at its inner edge portion into a downwardly turned supporting flange or wall 11, also concentric to the skirt 6 and wall 9 and which may have its terminal edge turned slightly as indicated at 12.

At equidistantly spaced points, the rib 8 is indented at 13 to provide inwardly overhanging nibs 14, the purpose 10 of which will be described hereinafter.

The previously described connecting ring structure is designed for removably attaching a smaller diameter can of the tear strip type upon a larger diameter supporting can. The supported or smaller can 15 has a bottom closure 16 double roll seam secured thereon at 17, and a top closure 18 double roll seam secured thereon at 19. A winding key 20 is attached to the top closure 18, as indicated in Figure 2. The larger or supporting can 21 also has a bottom closure double roll seam secured thereon at 22, and a top closure 23 double roll seam secured thereon at 24. It will also be apparent by reference to Figure 2 that the top closure 23 of the supporting or larger can has a winding key 25 attached centrally thereto.

In use, the connecting ring structure has its skirt 6 fitted over the top seam 24 of the larger or supporting can and roll crimped or curled onto said seam to securely attach the ring structure to said larger or supporting can. See Figures 2 and 4. It will be noted that in this mounting of the ring structure, the inner wall 11 engages as 30 a supporting column against the top surface of the top closure 23 of the larger or supporting can 21. It will also be apparent by reference to Figure 2 of the drawing that the annular wall 11 provides a well within which the winding key 25 is housed. The key is readily accessible through the opening into the well prior to attachment of the smaller or supported can 15 on the ring structure, or after said can has been snapped out of its ring support or attachment.

The smaller or supported can can be conveniently, and 40 yet removably, attached to the connecting ring structure and the underlying supporting or larger can 21 by merely snapping the bottom seam 17 thereof, under the retaining nibs 14, said seam being snugly, but removably, received within the wall 9 and supported on the shelf 10 in the manner illustrated in Figures 2 and 4.

The arrangement of the parts is such that the attachment of the smaller or supported can 15 on the ring structure is quite secure, though removable in the initial mounting of the can, but after the smaller can has been 50 removed and replaced a few times, less effort will be required in the removal and remounting thereof.

While one form of the invention has been shown for purposes of illustration, it is to be clearly understood that various changes in the details of construction and arrangement of parts may be made without departing from the spirit and scope of the invention as defined in the appended claims.

I claim:

1. A can connecting ring structure of the character described comprising a horizontal planar annular body having a skirt depending from the outer edge portion thereof and dimensioned to embrace and form an attachment with the top closure securing seam of a supporting can, an annular rib upstanding from the inner edge portion of said body and merging inwardly into a vertical annular wall within which to snugly receive the bottom seam of a supported can, said wall merging at its lower terminus into a horizontal inwardly directed planar annular shelf on which the supported can rests, said rib having inwardly projecting nibs for removably snapping over the bottom seam of the supported can.

2. A can connecting ring structure of the character

described comprising a horizontal planar annular body having a skirt depending from the outer edge portion thereof and dimensioned to embrace and form an attachment with the top closure securing seam of a supporting can, an annular rib upstanding from the inner edge portion of said body and merging inwardly into a vertical annular wall within which to snugly receive the bottom seam of a supported can, said wall merging at its lower terminus into a horizontal inwardly directed horizontal planar annular shelf on which the supported can rests, said rib having inwardly projecting nibs for removably snapping over the bottom seam of the supported can and said shelf merging inwardly into a downwardly turned flange engageable as a supporting column against the top end closure of the supporting can.

3. The combination of a larger diameter supporting can and a smaller diameter supported can and a connecting ring removably attaching the smaller can in superposed relation on the larger can, each said can being of the tear strip type with bottom and top closures seam secured thereon and having a winding key attached centrally on its top closure, said ring comprising a horizontal planar annular body having a skirt depending from the outer edge portion thereof and securely embracing the top seam of the larger can, an annular rib upstanding from the inner edge portion of said body and merging inwardly into a vertical annular wall snugly but removably embracing the bottom seam of the smaller can, said wall merging at its lower terminus into a horizontal inwardly directed planar annular shelf supporting said smaller can, said rib having inwardly projecting nibs removably snapped over the bottom seam of the smaller can and retaining the same on said shelf, and said shelf merging inwardly into a downwardly turned flange engaging as a rib supporting column against the top end closure of the larger can and freely surrounding the winding key thereon so that the latter will be readily accessible upon removal of the smaller can from its mounting on the ring.

4. A can connecting ring structure of the character described comprising a generally flat horizontally dis-

posed ring body having as an integral part thereof and disposed at its outer peripheral edge a skirt depending from the ring body and dimensioned to embrace and form an attachment with the top seam of a supporting can, and an annular upstanding rib spaced inwardly from the skirt and bearing concentric relation thereto and dimensioned to embrace the bottom seam of a supported can of smaller size than the supporting can and having inwardly projecting nibs for removably snapping over such a bottom seam for removably attaching such a supported can on the supporting can.

5. A can connecting ring structure of the character described comprising a generally flat ring body having as an integral part thereof a skirt depending from the ring body and dimensioned to embrace and form an attachment with the top seam of a supporting can, an annular upstanding rib spaced inwardly from the skirt and bearing concentric relation thereto and dimensioned to embrace the bottom seam of a supported can and having inwardly projecting nibs disposed approximately at the level of said ring body for removably snapping over such a bottom seam for removably attaching such a supported can on the supporting can, and an annular shelf projecting inwardly of said rib in a plane paralleling the plane in which said ring body lies but spaced below the same a distance approximating the depth of the bottom seam of a supported can and on which the supported can rests.

6. Can connecting ring structure as defined in claim 5 wherein the annular rib rises above the plane of the ring body.

7. Can connecting ring structure as defined in claim 5 wherein there is included means depending from the shelf and engageable with a top portion of a supporting can to support the annular rib against objectionable downward flexure during the attachment of a can to be supported on the ring.
